UNITED STATES PATENT OFFICE.

JOHN GLEDHILL, OF NEW YORK, N. Y.

IMPROVEMENT IN TREATING HAIR FOR WEAVING.

Specification forming part of Letters Patent No. 10,555, dated February 21, 1854. ■

To all whom it may concern:

Be it known that I, JOHN GLEDHILL, of the city, county, and State of New York, have invented a new and useful Improvement in the Treatment of Hair for Weaving into Cloth; and I do hereby declare that the following is a full, clear, and exact description of the same, reference being had to the annexed drawings, making a part of this specification, in which—

Figure 1 is a longitudinal view, on an exaggerated scale, of part of a hair, exhibiting the effect of the treatment upon the end. Fig. 2 is a similar view with the hair in what I term the "serving-hook." Fig. 3 is a transverse view of the hair in the serving-hook.

Similar letters of reference indicate corresponding parts in each of the several figures.

The nature of my invention consists in raising a bulb or knob on either side of the hair by heat or chemical agency, for the purpose of preventing the hair slipping from the notched hook or other device by which it is wholly or partly drawn out from the bunch and served to the loom, and insuring its being properly caught and held as long as is necessary.

The property possessed by hair of forming a bulb or knob when singed by heat or submitted to the action of certain chemical agents is well known, and therefore needs no explanation. I consider that the method of raising the bulb or knob best suited for this purpose is to apply the ends of a bunch of hair to the surface of a heated metal plate, then all will be singed nearly or quite alike; but as there may be many other ways which would answer the purpose quite or nearly as

well I do not consider it necessary to limit myself to the use of this particular method.

The utility of the invention may be understood by reference to the drawings, in which A, Figs. 2 and 3, represents the end of the serving-hook, and *a* the notch which receives the hair and which holds it while the hook moves in such a direction as to draw it from the bunch. The hook catches the hair *b* a short distance behind its bulb *c* and moves toward the bulb, which prevents its slipping off and causes the hair to be carried by the hook. The bulb forms no impediment to the escape of the hair from the hook at the proper time, as the hair is drawn from the notch toward the points of the hook. Without such a bulb or knob so simple a contrivance as a notched hook could not be depended upon to effect the desired object, and it would be almost impossible to devise any means which would seize the hair and also relinquish it with sufficient readiness without the bulb.

What I claim as my invention, and desire to secure by Letters Patent, is—

Preparing hair for being woven into cloth by raising a bulb or knob at either end, substantially as shown and described, whether by the action of heat or by any chemical agent, whereby the hair is made capable of being readily seized and as readily relinquished by a device which serves it to the operating parts of the loom.

JOHN GLEDHILL.
